HANDLE CONSTRUCTION

Samuel Bohn, 606 Crescent Ave., Plainfield, N.J.
Filed Oct. 29, 1962, Ser. No. 233,781
8 Claims. (Cl. 16—111)

This invention relates in general to a handle construction, and more specifically to a handle construction for use on sliding doors, drawer fronts, and the like.

Heretofore, handles for sliding doors, drawer fronts and the like, often consisted of a handle construction of the type disclosed by a Keeler Patent No. 1,947,942 which is secured to a supporting surface by a pair of studs that are maintained in fixed relationship to one another. These studs are arranged to be inserted into a pair of holes formed in a supporting surface which are spaced apart at a distance equal to the spacing between studs. For this reason the use of such handle construction had only limited application; since their use is determined by the gauge or distance of the mounting holes in the door or drawer front for the various types of frame construction. Consequently handle constructions of the pull type described had to be stocked in various sizes to fit the gauge distance of the various non-standardized articles. This necessitated large inventories and the stocking of many different and odd sizes and shapes of handle constructions of the type described.

Therefore, an object of this invention is to overcome the disadvantages of the handle constructions of the pull type described by providing an improved handle construction which can be readily adapted to door or drawer fronts regardless of the spacing or gauge of the mounting holes therein.

Another object is to provide an improved handle construction which is relatively simple in construction, can be easily fabricated to any desired length, and which is positive in operation.

Another object is to provide an improved handle construction which is pleasing in appearance, and which handle construction can be firmly secured in place with a minimum effort.

A feature of this invention resides in the provision that the handle construction in accordance with this invention may be extruded or made to any length desired, and which can be readily secured to a frame structure or supporting surface having any hole spacing which is less than the length of the handle.

Other features and advantages will become more readily apparent when considered in view of the drawings and description in which:

FIG. 1 is a perspective view of the handle construction of this invention illustrated partly in section and as applied to a supporting surface or frame.

FIG. 2 is a plan view of the handle construction having parts shown in section.

FIG. 3 is a detail front view of the handle construction.

FIG. 4 is a detail rear view of the handle construction.

FIG. 5 is a detail view of the mounting plug.

FIG. 6 is a plan view of the mounting plug, and

FIG. 7 is a detail bottom view of the mounting plug.

Referring to the drawings, there is shown in FIGS. 1 to 4 the handle construction 10 of this invention. As shown it comprises an elongated angled-like member 11 having a pair of leg portions disposed at substantially right angles with respect to one another. In the illustrated embodiment the horizontally disposed leg portion 11A is made somewhat longer than the vertical leg portion 11B; however, the latter is made slightly thicker than the frame. It will be understood that the size and dimensions are not considered critical. Connected along

2

the free longitudinal edge of the horizontal leg portion 11A is an enlarged hand grasping or gripping portion 12; and it extends substantially coextensively with the length of the handle 11.

5 In accordance with this invention a T-shaped slot or channel 13 is formed in the vertically disposed leg portion 11B of the handle. It will be noted that the cross head portion 13A of the T slot 13 is vertically disposed, and that the stem portion 13B of the slot 13 is open to the rear of the handle. As shown in FIGS. 2 to 4, the slot or channel 13 extends the length of the handle.

10 Mounting of the handle to a suitable supporting surface, door or drawer front 14 or the like is attained by a pair of mounting plugs 15. Each of the mounting plugs 15 comprises a shank 15A having an enlarged or flanged head end 15B which is adapted to be received in the crosshead portion 13A of the T slot 13 with the shank portion 15A thereof projecting to the rear of the handle through the stem portion 13B of the slot 13.

15 With the arrangement described the mounted plugs 15 are retained within the slot 13, yet rendered readily adjustable along the length thereof. Thus the respective mounting plugs 15 may be spaced to accommodate any spacing between mounting holes 16 which are formed 20 in the supporting surface door or drawer front 14 for receiving the shank 15A of the plugs. As shown in FIG. 2, the holes 16 in the supporting surface 14 are made slightly longer than that of the shank 15A.

25 Each of the plugs 15 is provided with a tapped or threaded bore 17 for receiving a screw fastener 18 or the like. Thus to secure the handle 10 to a supporting surface 14, the mounting plugs 15 are adjusted to the spacing of the holes 16, and then inserted into the holes 16 in the frame structure 14 aligned therewith. The screws 18 are then threaded into the bore 17 of the respective plugs 15 from the other side of the supporting surface 14. By tightening the screws 18 the head or flange 15B of the plugs 15 are drawn tight against the shoulders 19 of the handle, thus keeping the handle 10 held tightly against the supporting surface, door front or the like 14.

30 The construction of the handle 10 described can be readily fabricated by the continuous extrusion of either a plastic or metal material wherein the various size handle lengths can be cut to any given size. Consequently very little if any machining of the parts is required. The plugs 15 can be readily positioned in place in the T slot of the handle. From the foregoing it will be readily apparent that the various size handles may be formed with a minimum of effort, and that a given handle size may be 35 readily adapted to any frame structure irrespective of the spacing between the mounting holes therein, as the mounting plugs are rendered readily adjustable within the slot.

9240 9245

along the length of said elongated slot, and a fastener adapted to be received in said plug for firmly securing said member in place on said supporting surface.

2. A handle construction comprising an elongated extruded member having a portion adapted to be fitted against a surface to which the member is to be attached, said portion being provided with an elongated T-shaped slot having a cross head portion and a reduced stem portion opening to the rear of said portion, and means for securing said member to a supporting surface, said means including a mounting plug having a flanged head portion, said flange head portion being adapted to be received in the cross head of said slot whereby said plug is rendered readily adjustable along the length of said elongated slot, and a fastener adapted to be received in said plug for firmly securing said member in place to said supporting surface.

3. A handle construction comprising an elongated extruded member having a vertical and horizontal leg portion, said vertical leg portion being adapted to be fitted against a surface to which the handle is to be attached, said surface having a pair of spaced apart holes formed therein, said vertical leg portion being provided with an elongated T-shaped slot extending coextensively of said vertical leg portion, and means for securing said member to a supporting surface, said means including a pair of mounting plugs each having a flanged head portion, said flange head portions of the respective plugs being adapted to be received in said slot, said plug being rendered readily adjustable along the length of said slot whereby said plugs may be aligned with the holes in said supporting surface, and a fastener adapted to be received in each of said plugs to draw said member firmly against said supporting surface.

4. The invention as defined in claim 1 wherein said slot is coextensive with the length of said member.

5. The invention as defined in claim 1 wherein said slot opens to an end edge of said member.

6. The invention as defined in claim 1 wherein the diameter of said flange of said plug is larger than the width of said reduced opening.

7. A handle construction comprising an extruded elongated member having a pair of integrally connected

leg portions disposed at substantially right angles with respect to one another, an enlarged hand grip portion connected to the longitudinal free edge portion of one of said leg portions, a T-shaped channel slot formed in said other leg portion of said member, said channel slot being substantially coextensive the length of said other leg portion, the stem portion of said T slot being opened to the rear surface of said other leg portion, a pair of mounting plugs, each of said plugs having a flanged head which is adapted to be received within the crosshead portion of said slot whereby said plug may be slidably adjustable along the length of said slot for adapting said plugs to be spaced to accommodate the distance between holes formed in a supporting member, each of said plugs having a tapped hole therein, and a screw means adapted to be threaded into the tapped hole of each plug to firmly secure the handle to a supporting surface.

8. A handle construction comprising an extruded elongated member having a pair of integrally connected leg portions disposed at substantially right angles with respect to one another, an enlarged hand grip portion connected to the longitudinal free edge portion of one of said leg portions, a T-shaped channel formed in said other leg portion of said member, said channel being substantially coextensive the length of said other leg portion, the stem portion of said T being opened to the rear surface of said other leg portion, a pair of mounting plugs, each of said plugs having a stud portion and a flanged head portion, said flange head portion being larger than the stem portion of said slot and adapted to be received within said channel whereby said plugs may be slidably adjustable along the length of said channel for alignment with holes formed in a supporting surface, each of said plugs having a tapped hole therein, and a screw means adapted to be threaded into the tapped hole of each lug for the side of the supporting surface opposite the side to which said handle is secured to firmly secure the handle to a supporting surface.
